UNITED STATES PATENT OFFICE.

GEORGE D. WHITCOMB, OF CHICAGO, ILLINOIS.

PICK FOR MINING-MACHINES.

SPECIFICATION forming part of Letters Patent No. 280,541, dated July 3, 1883.

Application filed November 10, 1882. (No model.)

To all whom it may concern:

Be it known that I, GEORGE D. WHITCOMB, a citizen of the United States, residing at Chicago, in the county of Cook, in the State of Illinois, have invented a certain new and useful Improvement in Picks for Coal-Mining Machines, which is fully set forth in the following specification, reference being had to the accompanying drawings, in which—

10. Figure 1 is a side view of my improved pick. Fig. 2 is a section on the line *x x* in Fig. 1, showing one edge of the pick. Fig. 3 is a section on the same line, showing the other or opposite edge.
15. The same letters denote the same parts in all the figures.

My invention relates to picks for use in coal-mining machines. In my Patent No. 232,792, dated September 28, 1880, I have described a form of pick for this purpose which I find to be well adapted to the ordinary uses of coal-mining. Experience shows, however, that it is desirable a mining-machine should be provided with a variety of picks adapted to different kinds of strata and to cutting passages of different shapes; but coal differs in different mines, and sometimes the strata to be cut are of a tough nature and will not fracture freely under the blow of the pick, in which case the use of a pick of the form shown in the patent above named will result in leaving a cutting-face diversified by deep pockets and jagged projections, and on subsequent strokes the pick glances off from the points of the latter and sticks in the pockets. When the material

to be wrought is of this nature, I find it useful to employ a pick such as I will now proceed to describe.

The general conformation of the pick is the same as that described in the patent referred to; but in place of one of the points I make a nearly straight edge, B, rather less than an inch long, its direction being nearly at right angles to that of the V-shaped edge A, which joins the two points. At its other end this V-shaped edge terminates in a point, C.

In use the pick may be arranged with the short edge B either uppermost or at the bottom of the cut, according to the location of the harder material which it is designed to act upon. In operation this short edge strikes against the jagged points of the uneven face, and, acting in conjunction with the vertical V-shaped edge, will hold the pick in the desired position and prevent glancing.

What I claim as my invention, and desire to secure by Letters Patent, is—

1. A chisel-pick having a front edge receding from each of its ends toward the middle, and having at one of these ends a short edge transverse to the plane of said front edge, substantially as and for the purpose described.
2. A pick having the notched chisel-edge A, with the point C at one of its ends and the transverse edge B at the other, substantially as and for the purpose described.

GEO. D. WHITCOMB.
